HEINRICH F. E. BAESELER, OF DRESDEN, GERMANY, ASSIGNOR TO THE FIRM: AKTIEN-
GESELLSCHAFT VORM. SEIDEL & NAUMANN, OF DRESDEN, GERMANY.

TYPEWRITER-ACCENT-KEY MECHANISM.

Application filed May 3, 1922. Serial No. 558,217.

To all whom it may concern:

Be it known that I, HEINRICH FRANZ EDMUND BAESELER, citizen of the German Empire, and resident of Dresden, Saxony, Germany, have invented certain new and useful Improvements in a Typewriter-Accent-Key Mechanism, of which the following is a specification.

The invention refers to a device in typewriters for writing accents on letters as is needed for instance with the French language. The invention has for its object to provide improved means for this purpose as regards a cheaper manufacture as well as a more reliable function and it furthermore has the advantage that it renders it easy to change anyone of the normal keys into one bearing an accent instead of a letter.

The invention consists in using thoroughly separate members, which in no way interfere or coincide with the members actuated by the normal keys, for directly locking the ratchet-wheel when an accent key is touched. With a device of this kind the very beginning of the movement of the accent key can be utilized for effecting the locking of the ratchet wheel thus simply rendering the normal movements of those members inefficient which otherwise cause the carriage to move on and which thus need not in any way be modified. Heretofore this was unavoidable. For either the locking of the ratchet-wheel was effected by members which complicated the entire lever-mechanism or it was done in a way which caused the necessity of altering the actuation of the ink-ribbon, or in a way that the carriage after being locked was only freed again by the following touch of another key and this one had to be effected with greater power in order to accomplish that.

In the drawings are shown by way of example for a machine with a universal bar those parts which serve for the object of the invention. In Fig. 1 the parts are shown in the position of inoperativeness, in Fig. 2 in the position when the ratchet-wheel is locked and the accent key just touching the uni-

versal bar, the latter however still in rest, and in Fig. 3 in the position where the accent key touches the paper roller and consequently the ink-ribbon is lifted and the ratchet-wheel locked.

The key-lever 2 has its pivot at 7 and transmits its movement in a known manner by way of the intermediary lever 8 onto the type bar 4, which swings round the pivot 9. The type bar 4 is provided with a small projection 3 which, when the type bar approaches the end of its movement towards printing position is adapted to strike the universal bar. Caused by the horizontal movement of the universal bar, the fork (6), carrying the ink-ribbon, is raised by means of the bell crank lever 10, which has its pivot at 11, and of the rocking lever 12 which swings round pivot 13. On the other hand, by means of the rod 14 the ratchet-latch 15 is raised out of contact with the ratchet-wheel, thereby setting the carriage free for a latching movement. The ratchet-wheel 19 is subject to the influence of the spring which draws the carriage and thereby tends to turn in the direction of the arrow.

The levers 16 are only provided for keys carrying an accent-character and swing round the pivot 17. The latch 1 swings round the pivot 18 and is driven through the key (2) by way of levers 16/20.

The way of operating is as follows: As soon as an accent-key is being touched, latch 1 immediately engages the ratchet-wheel, and prevents the ratchet-wheel from turning, when after touching the paper roller projection 3 of type bar 4 pushes against the universal rail 5, and this one transfers this movement by way of rods 10/14 onto latch 15 which would thus release the ratchet-wheel for a latching movement.

I claim:

The combination with a typewriter or similar writing machine having a moving platen, a pawl and ratchet wheel mechanism for controlling the movement of said platen type bars, a key for each type bar and means

actuated by said type bars for actuating said pawl mechanism, of a pivoted lever projecting beneath said key and adapted to be actuated when said key is depressed, said lever articulated with a pivoted latch adapted to immediately engage said ratchet wheel when said key is depressed and prevent the normal actuation of said ratchet by said pawl, said latch and lever constructed and ar-

ranged to cause said latch to move out of engagement with said ratchet wheel when said key is released.

Signed at Dresden, Saxony, Germany this 28th day of March, A. D. 1922.

HEINRICH F. E. BAESELER.
